UNITED STATES PATENT OFFICE

HARRY A. COWARDIN, OF MARION, OHIO, ASSIGNOR OF ONE-HALF TO SAMUEL P. COWARDIN, OF RICHMOND, VIRGINIA

OIL-RELAY GOVERNOR

Application filed January 20, 1928. Serial No. 248,261.

My invention relates to oil relay governors.

It is the object of my invention to provide a governor in which a fluid pressure system operated by the engine which is being governed serves to shift the cam shaft on the engine which controls the amount of fuel supplied to the engine, and to further provide a governor to control the extent of application 10 of such fluid pressure means to maintain a given engine speed, as desired.

In particular, it is the object of my invention to provide a manual setting control for positioning the governor with respect to the 15 fluid pressure system which it controls in order to control the stopping and running of the engine.

Referring to the drawings:

Figure 1 is a diagrammatic view of the 20 governor mechanism and the engine to which it is attached.

Figure 2 is an enlarged section through the governing mechanism, showing the parts in stopped position.

25 Figure 3 is a similar view showing the parts in intermediate position as the governor is proceeding to correct the engine speed as the result of a full load being applied before the camshaft moves.

30 Figure 4 is a similar view showing the parts in position to run.

It will be understood that my invention is applicable either to a separate fluid pressure supply to control the system or it is applicable to the circulation system for lubrication 35 of an engine.

I preferably desire to employ my invention in connection with an injected fuel type of oil engine.

40 This particular invention is of that type in which the camshaft may be moved bodily by a system of levers for adjusting it from stopping to running position, and by which simultaneously the position of the governor arms is modified with respect to the cam- shaft.

45 Referring to the drawings in detail, 1 is an engine connected by pipes 2 and 3 to a lubrication pump 4 driven by the engine by the shaft 5. This pump is connected by the pipe

6 to a fluid pressure cylinder 7. The walls of this cylinder are formed by a tubular bearing sleeve 8, which supports the camshaft 9 as a piston. The sleeve 8 is carried within a casing cylinder 10, which is part of a general enlarged casing 11. The camshaft 9 has a centrally arranged passageway 12 opening through the end of the camshaft communicating with the cylinder 7. This passageway 12 proceeds an appreciable distance throughout the length of the camshaft and discharges laterally through the passageway 13 into the casing 11.

The discharge through the passageway 13 of fluid pressure accumulated within the cylinder 7 is controlled by a sliding sleeve 14 carried on the camshaft. This sleeve is reciprocated on the camshaft by the arms 15, which are a part of the governor construction, which consists of the arms 15 and the arms 16 connected by the link 17 carrying the weights 18 and restrained in their outward movement by the cross springs 19, which are connected to the respective groups of arms. The arms 16 are mounted upon a collar 20, which is prevented from moving in one direction by the stud 21 on the camshaft 9.

Engaging this collar 20 is a yoke on the lever 22. This lever is pivoted at 23, is actuated by a pitman 24, which in turn is actuated by the lever 25. The movement of this lever 25 serves to shift the governor and the camshaft axially. The positioning of the lever at any given position fixes the relative position of the governor with respect to the cylinder 7.

The collar 20 is mounted by a spline 26 upon the camshaft so that the governor will rotate with the camshaft. The camshaft is surrounded by a helical spring 27 engaged at either end by a ball bearing 28. One of these ball bearings engages the casing 11 and the other the stop 29 on the camshaft. The camshaft carries the usual cam 30, of which there may be any number, operating the roller 31 of the fuel injection mechanism 32. The casing is provided with a return pipe 33, which returns the fluid from the casing discharged from the fluid pressure cylinder to the reservoir 34, whence it passes by the pipe

35 back to the pump 4. The camshaft 9 is rotated by the gears 36 and 37, or by any other suitable mechanism.

The camshaft is provided with a supplementary discharge passageway 38, which is normally concealed and closed by the sleeve 8, but which is open when the engine achieves excessive speed and thereby the pump builds up excessive pressure so that it 10 forces the camshaft to an unusual position to the right hand, thus opening up the passageway 38 immediately discharging the fluid pressure and causing the stopping of the engine by the camshaft shifting under the action of the spring to its extreme lefthand position. This condition will arise only when the governor has become inoperative.

Method of operation

20 When the handle 25 is moved to running position the collar 20 is moved to the right hand so that the valve sleeve 14 may more readily, upon a given speed, control and cover the port 13, thus causing the fluid pressure from the pump to force the camshaft longitudinally against the spring 27, bringing the cams 30 into a position to supply adequate fuel to the engine for the load it is desired the engine shall carry.

30 If the handle is brought to the stop position then the sleeve 20 is moved to the left hand and by so doing the valve sleeve 14 is moved to a position where it cannot cover the port 13 so that the fluid pressure will discharge therethrough freely, and the engine will come to a stop as the camshaft will take a position where inadequate fuel will be supplied by the cam mechanism operating through the oil injection mechanism to support the engine operation. In the event that the governor does not work the safety outlet 38 will permit the oil in the cylinder 8 to escape without the necessity of the passage 13 being uncovered. This is due to the fact that 45 pressure is built up in the cylinder 8, which forces the camshaft to its extreme righthand position.

The hole 38 is also used in starting by moving the camshaft to the right by the lever 25.

50 This permits immediate exhausting of fluid during starting. Under such condition of starting the collar 20 is moved to the extreme right engaging the collar 21, thereby manually moving the camshaft.

55 I desire to comprehend within my invention such modifications as may be clearly embraced within my claims and the scope of my invention.

Having thus fully described my invention, 60 what I claim as new and desire to secure by Letters Patent, is:

1. In combination, means for creating fluid pressure, a camshaft adapted to be moved axially thereby, a governor, a cam rigidly mounted on said camshaft, means to rotate

the camshaft, a manually operated means adapted to axially position said governor means on the camshaft.

2. In combination with an engine, of a lubricant supply pump adapted to supply lubricant under pressure, a camshaft adapted to be moved axially thereby, means for passing lubricant through said camshaft to discharge laterally thereof, means for returning the discharge lubricant to the pump, governor means adapted to rotate with the camshaft, valve means carried by the governor for regulating the discharge of the lubricant through the camshaft, and manually operated means adapted to adjust the position of said governor axially of said camshaft.

3. In combination, a camshaft, means to rotate the camshaft, a centrifugally operated governor mounted thereon adapted to move therewith and move longitudinally thereof, fluid pressure means adapted to move said camshaft longitudinally, yielding means to resist said movement, and manually operated means adapted to adjust said governor on said camshaft axially thereof, and means associated with said governor for regulating the application of the fluid pressure for the longitudinal movement of the camshaft.

4. In combination with an engine, means for creating fluid pressure, means for rotating the camshaft, a camshaft having cams thereon for regulating the supply of fuel to the engine, a casing in which said camshaft operates, a fluid pressure cylinder in said casing in which said camshaft operates as a piston, said camshaft having a port therethrough discharged outside of the cylinder and communicating with the interior of the cylinder, centrifugally operated governor slidably mounted on said camshaft adapted to rotate therewith, valve means controlled by said governor for controlling the discharge port in said camshaft, and manually operated means adapted to move said governor axially on said camshaft without disturbing its rotation therewith, and yielding means adapted to resist the axial movement of the camshaft under fluid pressure.

5. In combination with an engine, means for creating fluid pressure, means for rotating the camshaft, a camshaft having cams thereon for regulating the supply of fuel to the engine, a casing in which said camshaft operates, a fluid pressure cylinder in said casing in which said camshaft operates as a piston, said camshaft having a port therethrough discharged outside of the cylinder and communicating with the interior of the cylinder, centrifugally operated governor slidably mounted on said camshaft adapted to rotate therewith, valve means controlled by said governor for controlling the discharge port in said camshaft, manually operated means adapted to move said governor axially on said camshaft without disturbing its rotation therewith, and

yielding means adapted to resist the axial movement of the camshaft under fluid pressure, said valve means consisting of a sleeve reciprocating on said camshaft and said governor consisting of spring connected arms connected to a sleeve splined to said camshaft on one side and the valve sleeve on the other side, yielding means for resisting the outward movement of said arms and weights on said arms.

6. In combination with an engine, means for creating fluid pressure, means for rotating the camshaft, a camshaft having cams thereon for regulating the supply of fuel to the engine, a casing in which said camshaft operates, a fluid pressure cylinder in said casing in which said camshaft operates as a piston, said camshaft having a port therethrough discharged outside of the cylinder and communicating with the interior of the cylinder, centrifugally operated governor slidably mounted on said camshaft adapted to rotate therewith, valve means controlled by said governor for controlling the discharge port in said camshaft, manually operated means adapted to move said governor axially on said camshaft without disturbing its rotation therewith, yielding means adapted to resist the axial movement of the camshaft under fluid pressure, said valve means consisting of a sleeve reciprocating on said camshaft and said governor consisting of spring connected arms connected to a sleeve splined to said camshaft on one side and the valve sleeve on the other side, yielding means for resisting the outward movement of said arms, and weights on said arms, and said manually operated means consisting of a yoke engaging said splined sleeve, said yoke having a system of levers connected thereto for moving the yoke with the associated governor parts axially on said camshaft without disturbing its rotating with the camshaft.

In testimony whereof, I affix my signature.

45 HARRY A. COWARDIN.
